UNITED STATES PATENT OFFICE.

EDMONDSON WARRIN, OF UPPER MONTCLAIR, NEW JERSEY.

DESIGN FOR A COCKTAIL SHAKER OR SIMILAR ARTICLE.

Application filed October 20, 1928. Serial No. 28,575. Term of patent 7 years.

To all whom it may concern:

Be it known that I, EDMONDSON WARRIN, a citizen of the United States and resident of Upper Montclair, Essex County, New Jersey, have invented a new, original, and ornamental Design for a Cocktail Shaker or Similar Article, of which the following is a specification, reference being had to the accompanying drawing, forming part thereof.

In the drawing is shown in Fig. 1, in elevation, a cocktail shaker, or similar article, showing my new design; in Fig. 2 is shown a plan or top view of the same.

I claim:—

The ornamental design for a cocktail shaker, or similar article, as shown.

EDMONDSON WARRIN.
